US00D999708S

(12) United States Design Patent (10) Patent No.: US D999,708 S
(45) Date of Patent: * Sep. 26, 2023

(54) MODULAR WALL MOUNT FOR A VEHICLE

(71) Applicant: Adventure Wagon LLC, Tualatin, OR (US)

(72) Inventor: Chad Smith, Portland, OR (US)

(73) Assignee: Adventure Wagon LLC, Portland, OR (US)

() Term: 15 Years

(21) Appl. No.: 29/757,578

(22) Filed: Nov. 6, 2020

(51) LOC (14) Cl. 12-16

(52) U.S. Cl.

USPC D12/412

(58) Field of Classification Search

USPC D12/406-414; D32/35, 58; D6/513-514, D6/317-319

CPC B62J 9/003; B62J 7/06; B62J 9/001

(57) CLAIM

The ornamental design for a modular wall mount for a vehicle, as shown and described.

DESCRIPTION

FIG. 1 is a top, front perspective view of a modular wall mount for a vehicle in accordance with a first embodiment of my new design;

FIG. 2 is a bottom, rear perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof;

FIG. 9 is a top, front perspective view of a modular wall mount for a vehicle in accordance with a second embodiment of my new design;

FIG. 10 is a bottom, rear perspective view thereof;

FIG. 11 is a front elevation view thereof;

FIG. 12 is a rear elevation view thereof;

FIG. 13 is a right elevation view thereof;

FIG. 14 is a left elevation view thereof;

FIG. 15 is a top plan view thereof; and,

FIG. 16 is a bottom plan view thereof.

1 Claim, 12 Drawing Sheets
